HENRY RODES, OF CLARENCE CENTRE, NEW YORK.

Letters Patent No. 69,486, dated October 1, 1867.

IMPROVEMENT IN COMBINED CORN-PLANTER AND PLASTER-DROPPER.

The Schedule referred to in these Letters Patent and making part of the same.

TO ALL WHOM IT MAY CONCERN:

Be it known that I, HENRY RODES, of Clarence Centre, in the county of Erie, and State of New York, have invented a certain new and useful Improvement in Combined Corn-Planters and Plaster-Droppers; and I do hereby declare that the following is a full and exact description thereof, reference being had to the accompanying drawings, making part of this specification.

Figure 1 is a plan of my improved machine.

Figure 2, a vertical longitudinal section.

Figure 3, an enlarged view, showing a section through the hoppers.

Figure 4, an end view of the operating cam and friction-roller.

Figure 5, a plan of one of the slides of the plaster-dropper.

Like letters of reference indicate corresponding parts in all the figures.

My invention consists essentially in the combination of a corn-planter and plaster-dropper, having the dropping apparatus of each so connected as to open the one and close the other simultaneously; also in the special arrangement of the dropping apparatus; also in the employment of a gauge-slide in combination with the plaster-slide for measuring the amount of plaster dropped at once; also in the arrangement of parts for raising and lowering the drill-tooth and coverer; also in the employment of an adjusting gauge and elastic connection in combination with the hinged plaster-discharge tube for directing the plaster in the tube; and finally, in the general arrangement of the machine.

As represented in the drawings, A is a main frame of suitable construction, and B B the driving-wheels. In this frame, at suitable distances apart, and on opposite sides, are mounted the corn hoppers C C and plaster-hoppers D D. Across the frame at a suitable position is situated a rock-shaft, E, that receives motion by means of a roller, *a*, on its crank end *b* coming in contact with a triangular-shaped cam, *c*, which is fast to the driving-wheel. The reaction of the shaft to produce the rocking motion is accomplished by a spring, *d*, fig. 1, wound round the shaft, or by some equivalent means. In line with the hoppers the shaft is provided at each end with a stiff arm, *f*, which operates the dropping arrangement connected with the corn and plaster-hopper. This arrangement consists of slides F and G, connected at *g g* to the arm, and resting respectively under the hoppers. The corn-slide F is simply a straight bar having a seed-cavity, *h*, whose capacity is measured by a gauge, *i*, moved up or back, and fixed in any desired position by a set-screw, as shown in fig. 3. A brush, *k*, is situated in the hopper in such position as to prevent undue escape of the corn. At each reciprocation the corn in cavity *h* is discharged in jointed tube *j*. The slide G which rests under the plaster-hopper has two plates, *l l'*, separated vertically such a distance as to measure the required quantity of plaster, and so situated, one past the other, that when one is under the outlet of the hopper the other is removed clear therefrom, and vice versa. In action it will be perceived that these plates will cut off and drop the required amount of plaster each time into the discharge-tube without allowing undue escape. It will also be noticed that when one hopper drops the other is closed, and vice versa. In order to gauge or measure the desired amount of plaster a plug, *n*, is made to slide in more or less beneath the hopper D, as shown in fig. 3. This plug is preferably connected with a lever, *o*, fig. 1, so that the operator can regulate the quantity of plaster dropped while going over the field, and without stopping the machine. By the employment of this arrangement of the dropping-slides in combination with the hoppers C D, it will be seen that both corn and plaster can be dropped at one and the same operation, the corn being first dropped and covered, and the plaster then dropping directly upon the hill. To accomplish this the movement of said slides is perfect, the one opening when the other is closed. This automatic action is necessary to accomplish the desired purpose, and the double action is so simple and unfailing that the plaster can be dropped upon the hill much more accurately than could be done by hand. I am not aware that a combined corn and plaster-dropper has ever before been known in which the dropping-slides have been arranged as a whole, with one movement, and in which the corn is first dropped and covered and the plaster then dropped upon the hill. In connection with the slide-plates *l l'* of the plaster-dropper the gauging-plug *n* is of the utmost importance, for it enables me to drop a large or a small quantity, as desired. In front of rock-shaft E is another, H, and at each end of this is a stiff arm, *p*, having a series of adjusting-holes, *g g*, in its end, for the attachment of a stirrup or clevis, *r*, fig. 2. This stirrup encloses a draw-bar, I, jointed to the front of the frame at *s*, and holding at its rear the hollow drill-tooth *t* which adjusts up and down over the jointed corn-tube *j*.

The pivot of stirrup r holds a friction-roller, u , for pressing down the bar I with as little friction as possible. Another double draw-bar, I' , is also jointed at s , and extending back, holds the coverer v which covers the drill. This coverer is made concave or hollowing on the under side, as shown, so as to concentrate the soil over the drill and round and smooth it off properly. The rear ends of draw-bars I I' are connected by a flexible connection, w , as shown. It will be perceived that by turning the arm p downward, as in fig. 2, the roller u will force the draw-bar I down and hold it in position to retain the drill-tooth t in the soil. At the same time the flexible connection w allows the coverer to drag over the drill and cover it, as before described. This connection is of much importance, for it allows a free and independent action of both the drill-tooth and the coverer. In going over inequalities, with the tooth in advance, of course it is necessary that the tooth should rise and fall without the coverer. At the same time that this effect is accomplished both the drill-tooth and the coverer will be raised from the ground by the single action of the arm p . The rock-shaft H is operated by a lever, K , attached thereto, moving over a quadrant, L , and secured in any desired position by adjusting-holes situated therein. The rock-shafts E H have arms y y connected by a chain or cord, Z , by which means the roller a is thrown away from cam e to disengage the same. The plaster-tube m is hung or pivoted at e , so as to swing freely. It has attached to its front side an elastic cord, a' , which draws it forward against an adjusting-gauge, b' , set forward or back by a set-screw. By this means it will be seen that the angle or position of the said tube may be adjusted forward or back exactly as required to adapt it to direct the plaster directly upon the planted hill. This arrangement is of much importance, for it enables the plaster to be dropped accurately, no matter what may be the distance of the hills or the condition of the soil. A shaft, M , extends through both plaster-hoppers, armed spirally with pins or teeth c' c' which properly agitate the plaster above the discharge openings of the hoppers. This shaft is driven by a band, d' , passing over pulleys f' .

What I claim as my invention, and desire to secure by Letters Patent, is—

1. The combination, with a corn-planter, C , and plaster-dropper D , of a dropping arrangement that by a single movement shall open the one and close the other automatically, and *vice versa*, as herein set forth.
2. The special combination and arrangement of the dropping apparatus, consisting of slides F G connected with the single arm f , and operating in the manner and for the purpose herein specified.
3. The combination of the sliding gauge-plug n with the slide-plates l l' , arranged as described, and operating in the manner and for the purpose specified.
4. The construction, combination, and arrangement of the draw-bars I I' , stirrup r , and connection w with the drill-tooth t and coverer v , as herein set forth.
5. The combination and arrangement of the elastic connection a' and the adjusting-gauge b' with the pivoted plaster-tube m , operating in the manner and for the purpose set forth.
6. The arrangement of hoppers C D with dropping-slides F G , the rock-shafts E H with connection z , the cam and roller e a , and the draw-bars I I' with stirrup r and connection w , the whole operating in the manner herein set forth.

In witness whereof I have hereunto signed my name in the presence of two subscribing witnesses.

HENRY RODES.
